U.S. Cl. D48—24

FIG. 1

FIG. 4

FIG. 1 is a view in side elevation of a torchlight showing my design;

FIG. 2 is a top view of FIG. 1;

FIG. 3 is a view similar to FIG. 1 but with the torchlight turned 90 degrees;

FIG. 4 is a bottom view of the torchlight with a portion of the tapered sides being omitted for convenience of illustration.

FIG. 5 is an elevational view similar to FIG. 3 but in reduced size illustrating a flame and a support post in conjunction with the torchlight.

The broken line showing of a support pole in FIGS. 1, 3 and 5 and of a flame in FIG. 5 is for illustration only.

I claim:

The ornamental design of a torchlight, substantially as shown and described.
